Specification of Letters Patent. Patented Nov. 24, 1914.

Application filed April 11, 1914. Serial No. 831,175.

To all whom it may concern:

Be it known that I, OSCAR O. BYRD, a citizen of the United States, and resident of St. Louis, in the county of St. Louis and State of Missouri, have invented new and useful Improvements in Insoles, of which the following is a specification.

My invention relates to insoles, of a type suitable for wear in shoes, boots, slippers and similar footwear, the purpose of my device being to promote the ease and comfort of the foot, and especially in instances where the foot is afflicted with corns, bunions, callouses or other analogous sources of discomfort.

More particularly stated, my insole is given such form as to so distribute the pressure, as between the footwear and the foot, that the tender or diseased portions of the foot are subjected to a minimum of crowding. In other words, a maximum of pressure is placed upon the healthy portions of the foot, in order to alleviate the pressure upon the diseased portions thereof.

My invention comprehends other features, as hereinafter set forth.

Reference is made to the accompanying drawings forming a part of this specification, and in which like letters indicate like parts.

Figure 1 is a top plan view of my insole. Fig. 2 is a bottom plan view of the same. Fig. 3 is a longitudinal section on the line 3—3 of Fig. 1, looking in the direction of the arrow.

The body portion of the insole appears at 3. An arch plate is shown at 4, and made up of sheet metal, preferably steel, or other rigid material. This arch plate is provided with a comparatively high or convex portion 5, and with a beveled edge 6, which in general outline is somewhat concave, as indicated in Fig. 2. The arch plate 4 is further provided at its front end or edge with protuberances 7, 8, separated by concave portions 9, 10, 11. The arch plate is held in position by aid of rivets 12 or analogous fastenings, whereby it is secured to the body portion 13 of the insole. This body portion is in this instance made of leather, but if desired it may be constructed of other suitable material. The body portion 13 is provided with one or more holes 14 placed in suitable position to receive a callous or the like, and each having for this purpose a

substantially conical portion 15, as may be understood from Fig. 3. That is to say, the wall of the body portion 13, immediately surrounding the hole 14, is thinned or beveled to a sharp edge, in order to prevent pressure upon the callous. The body portion 4 is further provided with flaps 16, 17, 18, 19, 20, 21, 22, or extending portions, which are adapted to be bent up slightly or curved to any desired extent, and to press against healthy portions of the foot. Between these flaps the body portion is provided with concave edge portions 23, 24, 25, 26, 27, and adjacent these concave edges the diseased portions of the foot are so positioned as to be subject to a minimum of pressure. The insole is further provided with a thin portion 28, where the center of the wearer's heel is to be placed. The adjacent portion 29, constituting the peripheral edge of the heel portion of the insole, is comparatively thick, as shown at 28. The heel of the insole is thus rendered essentially hollow.

It will be understood, of course, that not all diseased feet are alike, and therefore the precise conformity of the body portion 13 of the insole should be varied to suit different conditions. The particular form here shown for the insole, however, may be regarded as typical.

I do not limit myself to the exact construction illustrated, as variations may be made therein without departing from the spirit of my invention. Neither do I limit myself to the precise use here indicated for the device, as manifestly the invention admits of a wider range of adaptability.

Having thus described my invention, what I claim as new and desire to secure by Letters Patent is as follows:

1. A device of the character described comprising a rigid arch plate and a body member of comparatively soft material secured thereon, said body member being provided with certain flaps projecting forwardly and other flaps extending upwardly and outwardly from its side edges, so arranged that pressure upon diseased portions of the foot is relieved.

2. A device of the character described, comprising an arch plate of rigid material and a body member of comparatively soft material secured thereon, said body member being provided, between its edges, with portions of reduced thickness in order to

15 accommodate diseased portions of the wearer's foot, said body member being provided at its front and side edges with extending portions of tapering thickness, said side portions being adapted to be bent up around the edges of the wearer's foot.

3. In an insole, the combination of an arch plate of rigid material and a body member of leather secured upon said arch plate, said 10 body member being provided with a hole near its forward end and with a beveled edge bounding said hole in order to accommodate a diseased portion of the wearer's foot, said body member being further provided with flaps integral with its front and side edges and with concave edge portions located between said flaps, said flaps and said portion being of different thickness in order to distribute pressure of the wearer's 15 foot as between the healthy and the diseased portion of said foot.

4. An insole comprising a curved arch plate of rigid material, a body member of comparatively soft material secured thereon,

25 said body member being provided with certain flaps extending forwardly and side flaps extending upwardly and outwardly from its edges and having a bevel portion hollowed out between the side and rear edges.

5. An insole comprising an upwardly 30 curved arch plate of rigid material its front edge having convex extensions projecting therefrom and concave portions between said projections, and a comparatively soft material secured upon said arch plate and 35 having flaps projecting from its sides and forward end for the purpose of locally increasing pressure upon the healthy portions of the foot and relieving pressure from the diseased portions.

40 In testimony whereof I have signed my name to this specification in the presence of two subscribing witnesses.

OSCAR O. BYRD.
